CLAIM

The ornamental design for a multi-compartment food package, as shown and described.

DESCRIPTION

FIG. 1 is a front side perspective view of a multi-compartment food package, showing the new design;

FIG. 2 is a front elevation view thereof, the rear elevation being a mirror image thereof;

FIG. 3 is a left side view thereof, the right side view being a mirror image thereof;

FIG. 4 is a top plan view thereof;

FIG. 5 is a bottom plan view thereof;

FIG. 6 is a perspective view showing the multi-compartment food package in a folded configuration;

FIG. 7 is a perspective view of the multi-compartment food package, with detachable tops separated;

FIG. 8 is a perspective view of the multi-compartment food package, with one of the detachable tops separated; and,

FIG. 9 is a perspective view of the multi-compartment food package, with the compartments separated from each other. In the drawings, the short broken lines show perforations in the multi-compartment food package and form a part of the claimed design.
